[57] CLAIM

The ornamental design for a scoop for furnace ashes, as shown and described.

DESCRIPTION

FIG. 1 is a perspective view of a scoop for furnace ashes showing my new design;

FIG. 2 is a top plan view thereof;

FIG. 3 is a left side elevational view thereof;

FIG. 4 is a right side elevational view thereof; and

FIG. 5 is an end elevational view thereof.

The undisclosed bottom is substantially flat and unornamented.
